UNITED STATES PATENT OFFICE

135,548

DESIGN FOR AN AUTOMOBILE LAMP

Henry Rew Gross, Chicago, Ill.

Application December 2, 1941, Serial No. 104,429

Term of patent 7 years

To all whom it may concern:

Be it known that I, Henry Rew Gross, a citizen of the United States, residing at Chicago, Cook County, Illinois, have invented a new, original, and ornamental Design for an Automobile Lamp, of which the following is a specification, reference being had to the accompanying drawing, forming a part thereof.

Fig. 1 is a side elevational view of an automobile lamp showing my new design;

Fig. 2 is a top plan view thereof;

Fig. 3 is a front elevational view thereof.

The dominant features of the design reside in the portions illustrated in solid lines.

I claim:

The ornamental design for an automobile lamp, substantially as shown and described.

HENRY REW GROSS.
